UNITED STATES PATENT OFFICE.

JOSEPH C. DONNELLY, OF BARBERTON, OHIO, ASSIGNEE TO THE DIAMOND MATCH COMPANY, OF CHICAGO, ILLINOIS, A CORPORATION OF ILLINOIS.

SPLINT-DRYING MEANS FOR MATCH-MACHINES.

1,070,020.

Specification of Letters Patent. Patented Aug. 12, 1913.

Application filed November 19, 1912. Serial No. 732,168.

To all whom it may concern:

Be it known that I, JOSEPH C. DONNELLY, a citizen of the United States, and resident of Barberton, in the county of Summit and State of Ohio, have invented certain new and useful Improvements in Splint-Drying Means for Match-Machines, of which the following is a specification.

This invention relates to means for drying match splints, more particularly splints which have been impregnated with a solution of a chemical or chemicals which render the splints non-glowing after the same, as finished matches, have been ignited and the flame extinguished.

The invention is especially adapted for use in connection with, or as an attachment for, that class of continuous match machines wherein the splints are progressively set in parallel rows in an endless carrier and thereby transported through the match-making path, and in that relation it has been primarily designed to carry out in an economical and efficient manner the splint drying step of the process described in Letters Patent of the United States No. 1,044,153, dated November 12, 1912. Such process, briefly described, consists in impregnating the splints with a solution of chemicals of the character above mentioned, and then subjecting the wet impregnated splints, held in spaced relation to each other, to the action of a bath of material which is impervious to water, the said bath being maintained at a temperature sufficient to expel the solvent from the splints in the form of steam or vapor.

My invention concerns the operation of subjecting the splints to the action of a bath of highly-heated granular material, such as metallic pellets, in a manner to effect the rapid and thorough drying of the splints; and, broadly considered, comprises a structure wherein the said material is fed in a continuous stream to and along the path of the wet splints as the latter are impelled in spaced relation to each other by the splint carrier.

The invention also comprises various novel features of construction and operation whereby advantages are secured, as will be hereinafter described and claimed.

In the drawings Figure 1 is a sectional plan of a drier, embodying a good form of

my invention, certain parts being broken away and one of the bottom plates of the drying trough being removed in order to expose elements otherwise concealed. In this view a fragment of the splint carrier is indicated. Fig. 2 is a full longitudinal vertical section of the apparatus, as on the line 2—2 of Fig. 1; the impregnating tank and a part of the splint carrier as loaded with splints, being shown. In this view the stream of granular drying material is illustrated. Fig. 3 is a similar section, as on the line 3—3 of Fig. 1; the wall of the chambered section being broken away to expose parts of the burners and their adjuncts. Fig. 4 is a transverse vertical section of the apparatus, as on the line 4—4 of Fig. 2. Fig. 5 is a similar section, enlarged, of the upper part of the structure as on the line 5—5 of Fig. 2. Fig. 6 is a transverse section, as on the irregular line 6—6 of Fig. 2. Fig. 7 is a transverse horizontal section through one end of the apparatus, as on the line 7—7 of Fig. 2. Fig. 8 is a transverse section through the rotary electro-magnets and their adjuncts, as on the line 8—8 of Fig. 2. Fig. 9 is a detail, enlarged, of the contact rings and brushes of the electro-magnets. Fig. 10 is a sectional detail of the outer end of one of the "peep" tubes. Fig. 11 is a similar detail of the outer end of one of the primary ignition tubes for the burners.

A designates a portion of an endless carrier of any known or approved type into which the splints are inserted in consecutive rows and are thus transported in spaced relation to each other through the match making path.

B designates a tank, suitably-located beneath the carrier, adapted to contain a solution of a suitable chemical or chemicals into which the rows of depending splints on the chain are progressively dipped to a depth and for a period sufficient to accomplish the efficient impregnation of the splints; the chemical or chemicals being of such a nature as to render the splints non-glowing after the splints, as finished matches, have been ignited and extinguished. This tank is supported in any suitable manner, and the track for the chain is appropriately constructed to effect the depression of the traveling plates or sections above the top of the

tank so as to dip the splints in the impregnating solution, and then raise such plates or sections to withdraw the splints from the solution and permit the progress of the carrier with the impregnated splints.

6 C designates the splint-drying structure which is so constructed and organized that the traveling carrier bearing the wet impregnated splints is directed therethrough and 10 the splints are rapidly and thoroughly dried. This structure, in its preferred form, includes a trough into and through which the depending splints are impelled by the carrier. The bottom of this trough is inclined and the 15 carrier is directed in a path parallel thereto, or substantially so; suitable rails α' for the support and guidance of the carrier in its travel being provided at the sides of the structure.

20 As herein illustrated the main body of the structure comprises three sections 12, 12, 13, which are bolted together to constitute a casing of sufficient shape and size for its intended purpose. The outer sections 12 25 are similar in construction, except that they are right and left, and each includes an outer side wall 14 and a bottom 15 terminating in up-rising end walls 16. The middle section 13 includes a chambered portion 30 17 and end extensions 18, and it is interposed between the lateral sections to provide therewith two corresponding side chambers 19 and front and rearward chambers 20, 21, respectively, the functions of all of which 35 will hereinafter appear. The top of the middle section, terminates slightly below that of the others, and is provided with lateral ledges, which, in conjunction with similar ledges on the inner sides of the sections 12, support two inclined plates 22. These plates constitute the bottom of the trough above referred to. Through this trough flows a stream of granular heat-conducting material 23 into which the splints 40 on the carrier depend during their travel through the trough, such splints thus being surrounded by, and intimately subjected to the action of, the mobile granular constituents of the said material. This material, 45 in a highly-heated state, is caused to travel by and with the splints, and thus effect a progressive evaporation of the solvent from the impregnated splints.

The constituent units of the drying material 50 are preferably pellets, globular in form, or substantially so, so as to be freely movable and thus present only slight resistance to the opposing splints. These pellets may be highly-heated before their delivery to the trough, but I prefer to heat them during their travel therein while they are in actual contact with the splints, as thereby a more efficient drying action is insured. Accordingly I arrange within the 55 casing, directly beneath the bottom of the

trough, burners 24 for gas or other fuel. In the present instance there is a series of Bunsen burners beneath each bottom portion 22 of the trough, such burners extending through the side of the structure and 70 being provided with suitable regulating valves 25. The burners are conveniently lighted through tubes 26 provided for that purpose in the respective sides of the structure, each of the tubes being furnished at 75 its outer end with a hinged transparent cap 27 which is normally held in closed position by a suitable spring-latch, as 28. (See Fig. 11). That the flames at the burners may be readily viewed, I prefer to provide in 80 the walls of the structure a series of "peep tubes" 29. These tubes are arranged in line with the tops of the burners, and their outer ends are covered by transparent material 80, such as isinglass, which is held 85 in place by a ring 31. (See Fig. 10). The flames from the burners 24 impinge directly against the undersides of the bottom plates 22, and the products of combustion pass thence into ducts 32 formed in the 90 inner walls of the respective sections of the casing, thence to a common chamber 33 at one end of the casing, thence to and through an exhaust pipe 34 leading from said chamber to a suitable point of discharge. The 95 bottom plates are preferably provided on their undersides with ribs 35, extending longitudinally thereof, through which are openings 36 for the free passage of the products of combustion.

100 The mass of hot pellets tends to roll by gravity to the lower rearward end of the inclined bottom 22 of the trough, their descent being materially assisted by the traveling splints. Thence they are discharged upon suitably-disposed lower plates 37, which, being inclined in an opposite direction to the bottom of the trough as illustrated, direct them to the forward end of the casing. Thereupon the pellets are 110 raised to the upper receiving end of the trough, for a repetition of their travel, as will hereinafter appear. Within the casing beneath the lower plates 37, are also provided burners 24' for gas or other fuel, 115 whereby the pellets while passing along such plates are heated and effectually dried. The burners are herein illustrated, similarly to those above described, as of the Bunsen type. They extend through the bottom of 120 the casing, and are likewise provided with the usual regulating valves 25. Primary ignition tubes 26 and "peep" tubes 29 are also provided for the lower burners. The flames from these burners impinge directly 125 against the underside of the plates 37, and the products of combustion therefrom pass thence into the ducts 32 and are finally discharged through the pipe 34 as above described with respect to the upper burners. 130

The plates 37 are preferably ribbed on their undersides similarly to the upper plates constituting the bottom of the trough. The course of the products of combustion is indicated by the plain arrows. In the present instance the pellets are of steel, and the means for transferring them from the lower to the upper incline includes a pair of rotatable electro-magnets covered by brass tubes 38 and supported on shafts 39 within the forward chamber 20 hereinbefore referred to. These magnets are arranged one above the other with their peripheries slightly separated; power is applied from a suitable source to one of the shafts, and they are oppositely-rotated through intermeshing gear wheels 39' on their respective shafts; the desired quantity and depth of the mass of pellets within the trough being governed by the speed of the magnets.

Referring to Figs. 2, 3 and 7, 40 indicates the cores of the magnets and 41 the coils thereof. The wires for the coils pass through the centrally bored ends of the shafts 39 respectively, and are connected to contact rings 42 which are mounted on, and insulated from, said shafts. Electrical contact with these rings is effected by brushes 43 to which are connected the wires 44 leading from a suitable source of electric energy. The lower magnet in its rotation progressively attracts the pellets at the proximate end of the plates 37 and carries them to the space between the magnets. A suitably-disposed scraper 45 bearing upon the surface of the lower magnet strips the pellets therefrom and deflects them toward the upper magnet, which latter in its rotation attracts the pellets and carries them toward the bottom of the trough. A scraper 46 strips the pellets from the upper magnet and deflects them upon the bottom of the trough. Thus a continuous circulation, so to say, of the mass of pellets within the casting is effected; the heated pellets while passing through the trough being maintained at a substantially uniform depth and accomplishing the drying of the splints rapidly and thoroughly, and said pellets while moving along the lower incline being subjected, in turn, to the drying action of the heat from the underlying burners.

In order that the vapor or steam evolved from the solvent in the splints during the drying operation shall be readily removed, the following construction is employed; reference being had to Figs. 1, 3, 4 and 5; 47 is an elongated cap or channeled member, which is arranged upon the middle section 13 of the structure so as to bridge from end to end the chamber 17 of the latter and in effect medially partition the trough for the splints and pellets. The sides of this channeled member are provided with numerous perforations 48 which afford vents for air

which is supplied to the chamber 17 by means of a pipe 49 opening into the bottom of the latter. The air upon its entrance to the chamber is heated by contact with the walls of the latter, which air, escaping through the vents 48, is effectually diffused throughout the trough and across the path of the splints within the latter. This heated air, is directed to a pipe 50 leading to a suitable point of discharge, and thus the vapor or steam evolved from the solvent in the impregnated splints is carried off. In the present instance the escape pipe 50 leads from a chamber 51, formed by and between two spaced plates 52 which inclose the sides, ends and bottom of the structure, a suitable space for a jacket of insulating material 53 being provided between the inner plate and the structure. The sides of the outer plate 52 are extended up above the path of the splint carrier and are connected by a top plate 54. Thus lateral communication is afforded between the chamber 51 and the trough, and at the same time a covering or hood for the latter is provided. The ends of the chamber 51 are closed by flanged portions 55 of the structure, but communication between such ends of the chamber and the adjacent portions of the interior of the structure are afforded by suitably-disposed passages 56.

In the drawings the course of the air current throughout the structure is indicated by plain arrows. This current in its passage not only carries off the vapor or steam evolved from the solvent in the impregnated splints, but it also contributes to the drying operation. Furthermore it removes any slivers or broken splints which are lodged in the pellets or which may be rubbed from the splints by their contact with the pellets. In this connection it is to be noted that as a means to spread and shake up the mass of pellets as they leave the trough, and thus facilitate the removal of the contained slivers or broken splints by the air current, I arrange within the rearward spaces 21 of the structure, just below the discharge end of the trough, transverse bars 57, which intercept the descending material. A downwardly extending ledge 58 secured to this end of the structure, serves to direct the current from the spaces 21 to the adjacent discharge passage 56 and thus aid the escape of the splints and slivers.

It is to be understood that I do not confine myself to the particular form or details of construction herein shown and described, as the same may be variously modified without departing from the fair spirit of the invention.

I claim—

1. In splint drying means for match making machines having a splint carrier, a structure comprising means for supplying

- heated granular material to the path of the splints during their travel.
2. In splint drying means for match making machines having a splint carrier, a structure comprising means for feeding a stream of heated granular material into the path of and along with the splints during their travel.
3. In splint drying means for match making machines having a splint carrier, a structure comprising means for feeding granular material into the path of and along with the splints during their travel, and means for heating said material during its progress with the splints.
4. In splint drying means for match making machines having a splint carrier, a structure comprising means for supplying a stream of granular material to the path of the splints during their travel, means for heating said material during its progress with the splints, and means for heating said material after its action upon the splints.
5. In splint drying means for match machines having a splint carrier, a structure comprising means for establishing a continuous circulation of heated granular material through a path intersecting that of the splints on the carrier.
6. In splint drying means for match making machines having a splint carrier, a structure comprising means for supplying a stream of granular material to the path of the splints during their travel, means for heating said material during its progress with the splints, means for heating said material after its action upon the splints, and means for returning said material to the supplying means.
7. In splint drying means for match machines having a splint carrier, a structure comprising a support adjacent to which the splints depend during their travel, a lower support, and means for raising granular material from the lower support to the upper support and into the path of the traveling splints, whereby the said material is carried along the upper support by the said splints and discharged therefrom upon the lower support.
8. In splint drying means for match making machines having a splint carrier, a structure comprising an inclined support adjacent to which the splints depend during their travel, and means for feeding pellets of heat-conducting material to the upper end of said trough, whereby such pellets are caused to pass upon and along said trough and into the path of the traveling splints, and means for heating the said pellets.
9. In splint drying means for match making machines having a splint carrier, a structure comprising a support into which the splints depend during their travel, magnets for supplying metallic pellets to the said support, whereby said pellets are fed into the path of and along with the traveling splints, means for heating the pellets, and means for returning the pellets to the field of the magnets after the pellets are discharged from said support.
10. In splint drying means for match making machines having a splint carrier, a structure comprising a support adjacent to which the splints depend during their travel, a rotary magnet at one end of said support, means for supplying metallic pellets to said magnet, and means for deflecting the pellets from the magnet to the said support and into the path of the splints.
11. In splint drying means for match making machines having a splint carrier, a structure comprising a support adjacent to which the splints depend during their travel, a rotary magnet at one end of said support, means for supplying metallic pellets to said magnet, means for deflecting the pellets from the magnet to the said support and into the path of the splints, and means for heating the pellets during their progress on said support.
12. In splint drying means for a match making machine having a splint carrier, a structure comprising upper and lower supports inclined in opposite directions to each other, means for guiding the splint carrier above the upper support so that the depending splints travel adjacent the latter, means for transferring drying material from the lower to the upper support, whereby said material is fed into the path of and along with the splints, and is thence discharged upon the lower support and returned thereby to the said transfer means, and means for heating the said material during its progress on the upper support.
13. In splint drying means for match making machines having a splint carrier, a structure comprising upper and lower supports inclined in opposite directions to each other, means for guiding the splint carrier above the upper support so that the depending splints travel adjacent the latter, rotary magnets and scrapers coating therewith for transferring metallic pellets from the lower to the upper support, whereby said pellets are fed into the path of and along with the splints, and are thence discharged upon the lower support and returned thereby to the said magnets, and means for heating the said pellets during their progress on the upper support.
14. In a splint drier, a structure comprising upper and lower supports inclined in opposite directions to each other, means for guiding a splint carrier above the upper support so that the depending splints travel adjacent the latter, means for transferring drying material from the lower to the upper support, whereby said material is fed

into the path of and along with the splints, and is thence discharged upon the lower support and returned thereby to the said transfer means, burners below the upper support, burners below the lower support, a discharge pipe for the products of combustion, and ducts leading from the burner chambers to said pipe.

15. In a splint drier, a structure comprising a support or splint-drying pellets, a chambered member beneath the same, a laterally-perforated cap on said member, extending longitudinally of the support and communicating with the space above the same, means for heating said chamber, and means for supplying air to said chamber.

16. In a splint drier, a structure comprising a support for splint-drying material, means for supplying a stream of said material to the support, spaced-walls incasing the structure and providing an air space in communication with the path of the drying material, and an exhaust pipe leading from said air-space.

25. 17. In a splint drier, a support for splint drying pellets, means for supplying a stream of pellets thereto, and means for establishing an air current across the path of the pel-

lets in order to carry off splints and slivers which are mixed with the pellets. 30

18. In a splint drier, a support for granular splint-drying material, means for supplying a stream of said material to the support, and means for breaking up the mass of material as it passes from said support. 35

19. In a splint drier, a support for granular splint-drying material, means for supplying a stream of said material to the support, means for breaking up the mass of material as it passes from said support, and 40 means for removing the splints and slivers which are mixed with the said material.

20. In a splint drier, a structure comprising a support for granular drying material, means for supplying a stream of such material to the support, and bars arranged below the discharging end of said support adapted to break up the mass of material as it passes from the said support. 45

Signed at Barberton, in the county of 50
Summit and State of Ohio this 11th day of
November A. D. 1912.
